UNITED STATES PATENT OFFICE

125,558

DESIGN FOR A CASKET OR ANALOGOUS ARTICLE

John A. Bertelsen, Los Angeles, Calif.

Application October 8, 1940, Serial No. 95,692

Term of patent 14 years

To all whom it may concern:

Be it known that I, John A. Bertelsen, a citizen of the United States, residing at Los Angeles, in the county of Los Angeles, State of California, have invented a new, original, and ornamental Design for a Casket or Analogous Article, of which the following is a specification, reference being had to the accompanying drawing, forming a part thereof.

Fig. 1 is a top plan view of the casket or analogous article, showing my new design;

Fig. 2 is a side elevational view thereof with the lid raised;

Fig. 3 is a side elevational view of Fig. 1; and Fig. 4 is an end elevational view thereof.

I claim:

The ornamental design for a casket or analogous article, substantially as shown.

JOHN A. BERTELSEN.
